MOBILE LOG SLASHER

Douglas O. Sanders, 402 Minneapolis Ave., and George
S. Finneman, 318 Maryland Ave., both of Duluth, Minn.
55803

Filed Oct. 26, 1966, Ser. No. 4,495

Term of patent 14 years

(Cl. D14—3)

FIG 1

FIGURE 1 is a perspective view of a mobile log slasher embodying our design and taken from one side thereof;

FIGURE 2 is a plan view thereof;

FIGURE 3 is a rear elevational view thereof; and

FIGURE 4 is a side elevational view thereof, taken from the side opposite that shown in FIGURE 1.

We claim:

The ornamental design for a mobile log slasher, as shown.
